UNITED STATES PATENT OFFICE.

EDWARD N. LODGE, OF COLUMBUS, OHIO.

PHOTOGRAPH-MOUNT.

Specification of Letters Patent. Patented Mar. 27, 1917.

1,220,354.

Application filed December 15, 1915. Serial No. 67,010.

To all whom it may concern:

Be it known that I, EDWARD N. LODGE, a citizen of the United States of America, and resident of Columbus, in the county of 5 Franklin and State of Ohio, have invented certain new and useful Improvements in Photograph-Mounts, of which the following is a specification.

This invention relates to mounts for photographs and ornamental cards, the said invention having for its object the provision of novel means for facilitating the application of the card to the bolder or mount, the said provision being of a nature to accomplish such result, as stated, without increasing the cost of production of the mount, it being possible to emboss the corner retaining socket members to produce the means for facilitating the application of the card 20 thereto in a single operation.

With the foregoing and other objects in view, the invention consists in the details of construction, and in the arrangement and combination of parts to be hereinafter more 25 fully set forth and claimed.

In describing the invention in detail, reference will be had to the accompanying drawings forming part of this specification wherein like characters denote corresponding parts in the several views, and in which

Figure 1 illustrates a view in perspective of a photograph mount embodying the invention;

Fig. 2 illustrates a plan view thereof showing a fragment of a card applied to one of the corner sockets;

Fig. 3 illustrates a sectional view on the line 3—3 of Fig. 2; and

Fig. 4 illustrates a sectional view on the line 4—4 of Fig. 2 with the card in dotted lines.

In these drawings 5 denotes the body of the mount, which member may be of any desired configuration but for convenience of illustration, it is here shown as rectangular in plan. Near the corners of the member or body 5, there are pockets or sockets 6 preferably made by embossing the stock or body so that the corners of a photograph or other sheet 7 may be retained by the said pockets or sockets.

During the embossing operation, a diag-

onally disposed slit 8 is made in the body or member 5 which forms one edge of the 55 pocket adapted for the reception of a corner of the photograph, it being understood that one such slit is produced at each pocket. In order to facilitate the insertion of the corner of a photograph in the pocket, the body or 60 member 5 is punctured or cut away as at 9 to form a clearance through which the corner of the photograph may be inserted so as to insure its finding its way under the embossed portion which forms the pocket. Of course, 65 these slits and cut away portions are formed at each pocket, as stated, and either end of the photograph may, therefore, be applied with equal facility and the initial movement of the edge of the photograph under 70 the embossed portion tends to so lift the embossed portion as to create clearance for the free passage for the corner of the photograph into position.

As has been stated heretofore, the production of the photograph mount embodying these improvements entails no additional cost in operation, the only additional cost being the comparatively small item incident to the production of the dies essential for cutting the slits and punching the apertures forming the clearances of which mention has been made.

I have shown the punctured portion as being semi-circular but it is obvious that the 85 configuration is immaterial and that other outlines may be adopted for the edges of the aperture without departing from the spirit of the invention or the scope of the 90 appended claim.

I claim:

In a photograph mount, a body, embossed pockets formed integral with the body and adjacent the corners thereof, one edge of each of the pockets being separated from the body by a slit, and each body portion having a semi-circular cut out portion forming in part a continuation of the slit for providing a clearance for the reception of the corners of the photograph.

In testimony whereof, I hereunto affix my signature in the presence of two witnesses.

EDWARD N. LODGE.
